Patented Oct. 14, 1975

237,204

TOY FIGURE

Samuel F. Speers, 120 Mount Hope St.,
North Attleboro, Mass. 02703

Filed Feb. 19, 1974, Ser. No. 443,827

Term of patent 3½ years

Int. Cl. D21—01

U.S. Cl. D34—15 AD

FIG. 1

FIG. 2

FIG. 3

FIG. 4

FIG. 5

FIG. 1 is a side elevational view of a toy figure showing my new design;

FIG. 2 is a front elevational view thereof;

FIG. 3 is a rear elevational view thereof;

FIG. 4 is a top plan view thereof; and

FIG. 5 is a bottom plan view thereof.

I claim:

The ornamental design for a toy figure, substantially as shown.
